UNITED STATES PATENT OFFICE

2,029,257

COOKING STOVE

Claude M. Dibble, Joliet, Ill., assignor to Moore Brothers Company, Joliet, Ill., a corporation of Illinois

Original application June 3, 1927, Serial No. 196,197. Divided and this application August 27, 1930, Serial No. 478,075. Renewed March 18, 1935

4 Claims. (Cl. 126—41)

This invention relates in general to a cooking stove construction and has more particular reference to a sliding drawer which forms a part thereof. This application is a division of my application for United States Letters Patent Serial No. 196,197, filed June 3, 1927, for Cooking stoves.

A principal object of the present invention is the provision of improved means for raising and lowering the broiler pan in an oven drawer.

10 A further important object of the invention is the provision, in connection with a broiler drawer having means for raising and lowering the broiler pan, of sight openings so arranged that the pan in its several adjusted positions may be readily observed without opening the drawer to the end that need for change of location may be readily determined.

20 Numerous other objects and advantages of the invention will be apparent as it is better understood from the following description, which, taken in connection with the accompanying drawing, discloses a preferred embodiment thereof.

On the drawing,

25 Figure 1 is a perspective view of a drawer embodying my present invention, parts being broken away and shown in section to disclose certain features of invention thereof;

Fig. 2 is a transverse sectional view through the drawer and parts carried by it shown in Fig 1;

30 Fig. 3 is a front elevation of the stove embodying the instant invention; and

Fig. 4 is a fragmentary detail taken substantially on the line 4—4 of Fig 3.

For the purpose of illustrating my invention I have shown on the drawing a kitchen stove or range in which the invention is or may be embodied. This stove comprises the usual open burner portion 1, upper baking oven 2, and lower broiler assembly 3, mounted together in the usual manner upon a supporting base 4, carried by legs 5. The broiler assembly includes a burner 6, mounted at the top of the broiler compartment and just beneath the baking oven, and adapted in the present embodiment of the invention to provide the desired heat by the burning of gas or other fluid fuel. A drawer 7 is provided to move in and out of the broiler compartment. The drawer of the drawing comprises a bottom wall 11, a front wall 12 and side walls 13 and 14. The side walls 13 and 14 are connected at their rear by a cross member 15. The front wall 12 is of appropriate shape and dimension to close the front of the broiler compartment to replace the usual broiler door.

5 Two rods or shafts 16 and 17 are arranged upon

the bottom 11 and extend from the front to back of the drawer and in bearing cleats or members 18 appropriately positioned. The shaft 16 is arranged wholly within the drawer and the shaft 17 extends from near the back of the drawer to 5 and through the front wall 12 and at the front of the drawer is bent upwardly to provide an arm 19 adapted to be swung, as will be presently more fully explained, to accomplish raising and lowering of the broiler pan.

10 The arm 19 is provided at its top with a pivot finger or like piece 21 adapted to be engaged in notches 22 provided in a quadrant 23 to secure the parts in their various adjusted positions.

Each shaft 16 and 17 is provided near its front 15 and rear ends with an arm 24 fixed for rotation or swinging movement with the shafts. The two arms 24 at the front are connected by a link 25 and similar connection is or may be provided between the two arms 24 at the rear. Thus constructed and arranged it will be apparent that upon movement of the upwardly extending arm 19 of the shaft 17 the four arms 24 will rock in unison with each other and in unison also with the swinging movement of the arm 19.

20 The two arms 24 at the rear are provided with forwardly extending pins 26 arranged through slots 27 formed in the rear cross-support 28. Similarly the two arms 24 at the front are connected to a cross-front support 29.

25 The broiler pan, generally indicated at 31, is provided with the usual side flanges 32 and front and rear flanges 33, which rear and front flanges are adapted to rest upon the back cross-support 28 and the front cross-support 29. The front and 30 back supports preferably have dimension approximately that of the distances between the inner faces of the side walls 13 and 14 and swinging movement of the arms 24 is accompanied therefore by vertical movement of the rear and 35 front cross-supports without appreciable horizontal shifting. This movement in turn imparts like movement to the broiler pan carried by it and the broiler pan is lifted and lowered directly from the flame. This movement is confined substantially to a vertical plane. Adjacent the wall 13 upwardly extending cleats 34 are arranged upon the bottom 11 to limit the downward movement of the arms 24.

40 In order that the broiling may be observed and 50 timely adjustment made, two sight openings are provided at the front of the stove and preferably just above the horizontal level of the top of the quadrant 23. Each of these sight openings comprises a transparent inset 35 preferably of glass 55

arranged in openings provided in the front wall of the drawer and held in place by a suitable holding frame 36.

Adjustable stop members 41 are pivoted at 42 at the tops and near the rear of the side walls 13. When these stops are arranged as shown in Fig. 1, to extend rearwardly, their shoulders 43 are in position to engage behind fixed stops 44 appropriately arranged within the chamber in which 10 the door slides. The door may be removed by pulling nearly to stop engaging position and then reaching in and swinging the adjustable stops forwardly on their pivots until they are arranged in horizontal position, in which position they may 15 pass beneath the fixed stops 44.

It is thought that the invention and many of its attendant advantages will be understood from the foregoing description, and it will be apparent that many changes may be made in the form, 20 construction and arrangement of the parts without departing from the spirit and scope of the invention or sacrificing all of its material advantages, the form hereinbefore described being merely a preferred embodiment thereof.

25 I claim:

1. In a stove, means forming a compartment open at one end, a drawer movable therein having sight apertures at the front, a broiler pan for the drawer, means operable from the front there- 30 of for adjusting the vertical elevation of the pan in the drawer, a fixed stop at the side of the compartment, and an adjustable stop member at the rear of the drawer to engage the fixed stop for limiting the outward movement of the drawer 35 and movable out of position to engage the fixed stop for removing the drawer.

2. In a stove, means forming a compartment open at one end, a drawer movable therein having a sight aperture at the front, a pan fitting loosely in the drawer, means operable from the front thereof for adjusting the vertical elevation 5 of the pan in the drawer, said means comprising a pair of shafts extending longitudinally in the drawer, arms projecting from the shafts, slotted cross pieces engaging under the ends of the pan, and means projecting from the ends of the 10 arms and engaging in the slots of the cross pieces for moving the pan in accordance with the movement of the shafts.

3. A stove, comprising a cooking compartment, 15 a source of heat at the top of the compartment, a tray adjustably supported within said compartment, means for adjusting the position of the tray comprising slotted cross pieces extending under opposite edges of the tray, arms with projections engageable in the slots of the cross 20 pieces, shafts secured to the arms, means for connecting corresponding arms of the shafts for moving the latter in unison, and a crank extension on one of the shafts for rotating the shafts together to raise and lower the tray. 25

4. The combination of means forming a cooking compartment, a tray movable therein, means for adjusting the position of the tray comprising slotted cross-pieces extending under opposite edges of the tray, arms with projections slidably in 30 the slots of the cross-pieces, shafts secured to the arms and rotatable in unison in the same direction, and means extending outside of the compartment for operating the shafts. 35

CLAUDE M. DIBBLE.
